UNITED STATES PATENT OFFICE.

ANTHONY FRICKER, OF CLEVELAND, OHIO.

SAND AND GRAVEL SPREADER.

Application filed December 23, 1918. Serial No. 268,035.

To all whom it may concern:

Be it known that I, ANTHONY FRICKER, a citizen of the United States, and resident of Cleveland, in the county of Cuyahoga and State of Ohio, have invented new and useful Improvements in Sand and Gravel Spreaders, of which the following is a description, reference being had to the accompanying drawings, which are a part of this specification.

The invention relates to a device for spreading sand or similar material upon the surface of a road during paving operations.

One of the objects of the invention is to provide a spreader which may be operated by being pushed ahead of a motor truck so that the sand or other material will be deposited over the freshly prepared road ahead of the truck, a feature which is especially advantageous in the making of roads in which a coating of bituminous material is spread upon a layer of rock and is then covered over with sand, gravel or finely crushed stone.

25 A further object of the invention is to provide means for spreading material over different widths of roadway.

A still further object of this invention is to provide a device of the class described 30 having means for readily adjusting the depth and width of the materials discharged therefrom.

With the above and other objects in view which will appear as the description proceeds, my invention resides in the novel construction, combination and arrangement of parts substantially as hereinafter described and more particularly defined by the appended claims, it being understood that such 40 changes in the precise embodiment of the herein disclosed invention may be made as come within the scope of the invention.

In the accompanying drawings, I have illustrated one complete example of the 45 physical embodiment of my invention constructed according to the best mode I have so far devised for the practical application of the principles thereof, and in which:

Fig. 1 is a perspective view of the device 50 embodying the invention; Fig. 2 is a transverse horizontal section taken on the line 2—2 of Fig. 1 and looking in the direction of the arrows; Fig. 3 is a view part in elevation and part in transverse horizontal section taken on the line 3—3 of Fig. 1 and looking in the direction of the arrows; Fig.

4 is a detail view of a portion of the under-side of the conveyor; Fig. 5 is a detail sectional view through one of the wheels and the conveyor.

In the drawings, the numeral 6 designates the spreader conveyor as a whole. This conveyor is made of a plurality of transversely extending plates 7 each of which is pivotally secured adjacent its ends to chains 8 by means of lugs 9 on the plates carrying pins 10 which pass through the links of the chain, adjoining plates being secured to adjoining chain links so that the front edges 11 of the plates slightly overlap the rear edges of the 70 adjacent plates as shown in Fig. 1.

The conveyor runs over two sets of rollers or wheels 13 which are mounted on shafts 14 secured to side frame members 15. Each roller 13 is provided with a centrally disposed annular groove 16 in which the chain 8 runs and with a plurality of radially disposed recesses 17 for receiving the projected ends of the pins 10 whereby a driving connection is formed between each set of rollers and the conveyor. The lower run of the conveyor forms a track upon which the device moves and is held flat between the rollers 13 by means of rollers 18 running on the chain links and carried by shafts 19 journaled in brackets 20 secured to the members 15. The upper run of the conveyor is supported and braced by a central plate shoe 21 and side plates 22 secured to transverse brace members 22' which are connected to 90 the members 15.

A top frame, consisting of uprights 23 and 24, side members 25, end members 26 and brace members 27, is secured to the frame members 15 by connections between the 95 members 23 and 24 and said members 15.

In order that the material may be spread to different depths upon the road and varying widths of road covered, I provide a gate which is adjustable vertically with respect 100 to the conveyor to vary the thickness of the layer of the material spread by the conveyor, and which is adjustable laterally so as to vary the effective delivery width of the conveyor.

The said gate comprises two plates 25', pivotally connected together at their inner ends 26' and provided at their outer ends with the bored and threaded bosses 28' which engage the threaded rods 27', whereby the 110 said plates may be vertically adjusted. The said rods 27' are rotatably mounted in bosses

28 carried by one end of the side-plates 29, which plates are pivotally mounted at their other ends 29' between the bearings 30', rigid with the side frame member 25. The inner 5 ends of said plates 29 are provided with channel guideways 30 in which extensions 31 of the plates 25' loosely fit. The plates 25' at their hinged connection have upturned lower edges to form a shoe 32 which will 10 press the advancing edges of the plates 11 of the conveyor downwardly in case said edges should project upwardly to such an extent as to engage the lower side edges of said plates 25'. The plates 25' carry a hinge 15 pivot 33 which is provided with a guide pulley 34 and a chain 35 passes over this pulley and around sprockets 36 carried by the rods 27' so that by turning either of these rods the plates 25' may be simultaneously adjusted vertically above the conveyor for the purpose previously described. The plates 20 25' are pivotally connected at their outer ends to collars 27 pivotally secured to the bosses 28' and having threaded bores and a 25 shaft 38 having oppositely threaded ends seated in said bores provides means for moving the outer ends of said plates toward or away from each other to vary the effective 30 delivery width of the conveyor, the side plates 29 swinging inwardly when the plates move inwardly on the turning of a hand-wheel 39 on the shaft 38.

For the purpose of feeding the material to be spread by the conveyor onto the same 35 I provide a hopper or bucket 40 pivotally secured at its dumping end to a shaft 41 carried by the top frame and adapted to be raised and lowered by means of cables 42 running over drums 43 on a shaft 44, pulleys 40 45 on the top frame and pulleys 46 on the bucket as shown in Fig. 1 with a pawl 47 and ratchet 48 for securing the cable against backward movement, the shaft 41 being turned by a crank 49 or other suitable means. 45 To enable the device to be pushed ahead of the propelling vehicle I provide bumpers 50 secured to or integral with the frame members 15.

With the construction above described the 50 plates 25' are set the desired vertical distance above the conveyor 6 and their outer ends are set to the width desired and the material fed to the conveyor from the elevated hopper 40. From the foregoing description, it will be readily apparent that the 55 control gate is in two parts or sections, the plates 29 forming one part and the plates 25' the other, and the section formed by plates 29, the lower edges of which are at all times 60 in close proximity to the bottom of the hopper which is formed by the upper run of the endless conveyor, controls the width at which the material is discharged from the device. The adjustment of the plates 29 to vary the 65 width at which the materials are discharged

is obtained by varying the distance between the ends of said plates remote from their ends 29' pivotally fixed to the frame. The other section, formed by plates 25' controls the depth at which the materials are discharged by reason of the adjustability of 70 said plates to vary the distance between their lower edges and the bottom of the hopper as formed by the top run of the conveyor. The adjustment of the plates 25' is 75 made independent of the adjustment of plates 29 by means of a hand crank which is engageable with either of the rods 27', as will be readily obvious.

The propelling vehicle pushing the 80 spreader ahead of it causes the conveyor to move over the rollers 13 and carry the material forwardly and deposit it in front of the advancing conveyor and propelling vehicle. Thus the sand or gravel may be laid 85 upon the freshly prepared road and much labor saved as it has heretofore been the practice to spread the sand or gravel upon the road by hand shovelling.

What I claim as my invention is:

1. A material spreader comprising a frame, a hopper carried by the upper portion of the frame, means for discharging material from the hopper, and means for controlling the depth and width of the material 95 as discharged from the hopper and including pivotally connected gates.

2. A material spreader comprising a frame, an endless belt mounted thereon, a hopper disposed above the upper run of the 100 endless belt, the upper run of the endless belt providing a conveyer bottom for the hopper, and an adjustable gate for regulating the depth and width of material delivered from the hopper by said conveyor bottom.

3. A material spreader comprising a frame, an endless belt mounted thereon, a hopper disposed above the upper run of the 110 endless belt, the upper run of the endless belt providing a conveyer bottom for the hopper, means at the discharge end of the hopper for regulating the width of material delivered therefrom, and a vertically adjustable gate for regulating the depth of the 115 material discharged from the hopper.

4. A material spreader comprising a frame, supporting wheels for the frame, an endless belt trained about the supporting wheels, the lower run of the belt affording a path for the wheels, a hopper disposed at the top of the frame, the upper run of the belt forming the bottom of the hopper and providing means for discharging material from the hopper, and a gate for controlling the thickness and width of the stream of material discharged from the hopper.

5. A material spreader comprising a frame, supporting wheels for the frame, said frame having its sides extended upwardly to form a hopper, an endless belt trained about 130

- the supporting wheels, the lower run of which frictionally contacts with a surface traversed to cause the supporting wheels to travel over the track, and the upper run of which forms the entire bottom of the hopper and causes material to be discharged therefrom, plates having their outer ends secured to the sides of the hopper and providing an adjustable discharge opening for the hopper for controlling the width of the stream of material discharged from the hopper, and a gate carried by the inner ends of the plates to control the discharge of material through the discharge opening.
- 15 6. A material spreader comprising a frame, supporting wheels for the frame, said frame having its sides extended upwardly to form a hopper, an endless belt trained about the supporting wheels, the lower run of which frictionally contacts with a surface traversed to cause the supporting wheels to travel over the track, and the upper run of which forms the entire bottom of the hopper and causes material to be discharged therefrom, plates having their outer ends secured to the sides of the hopper and providing an adjustable discharge opening for the hopper for controlling the width of the stream of material discharged from the hopper, and a gate carried by the inner ends of the plates and movable vertically to control the thickness of the stream of material discharged from the hopper.
- 20 7. A material spreader comprising a frame, supporting wheels for the frame, an endless belt trained about the supporting wheels, the lower run of the belt affording a path for the wheels, a hopper disposed above the upper run of the belt, the upper run of the belt forming the entire bottom of the hopper and causing material to be discharged therefrom, a plate swingingly secured to each side wall of the hopper adjacent its discharge end, means for swinging the inner ends of the plates toward and away from the center of the hopper to control the width of the stream of material discharged therefrom, a gate member carried by the inner ends of the plates, and means for moving the gate member vertically to control the thickness of the stream of material discharged from the hopper.
- 25 8. A material spreader comprising a frame, supporting wheels for the frame, an endless belt trained about the supporting wheels, the lower run of the belt affording a path for the wheels, a hopper disposed above the upper run of the belt, the upper run of the belt forming the entire bottom of the hopper and causing material to be discharged therefrom, a plate swingingly secured to each side wall of the hopper adjacent its discharge end, means for swinging the inner ends of the plates toward and away from the center of the hopper to control the width of the stream of material discharged therefrom, a two part medially pivoted together gate member vertically movably carried by the inner ends of the plates, and means for adjusting the gate member to control the thickness of the stream of material discharged from the hopper.

In testimony whereof, I affix my signature.

ANTHONY FRICKER.
